UNITED STATES PATENT OFFICE.

GEORGE F. WIKLE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

DEVICE FOR INSERTING BAGS.

Application filed October 6, 1924. Serial No. 741,952.

My invention relates to the manufacture of pneumatic tire casings and more particularly to devices for inserting expandable cores usually referred to as bags in the raw casings 5 preparatory to vulcanization.

It is an object of my invention to provide a device of the character stated which shall be positive in action and perform its operation expeditiously and with a minimum of wear 10 on the bag. Other objects will appear from the following specification and claims.

In the accompanying drawings which illustrate one embodiment of my invention

Figure 1 is a side elevation, and

Figure 2 is a view in the direction of the arrow in Figure 1.

Figure 3 is a side elevation with one of the side members removed and showing the cylinder partly in section.

Figure 4 is a section on line 4—4 of Figure 1.

Figures 5 and 6 are details of the folding pin and its controlling cam.

Figures 7 to 10 inclusive show diagrammatically the operative steps of the device.

Referring to the drawings the main frame of the device comprises a base 1 to which are secured two upright channel members 2 and 3 by means of angle irons 4 and 5. The 30 channel members 2 and 3 are placed with their channels facing each other as shown in Figure 4, thus forming a rectangular enclosure. Secured within this enclosure, adjacent the base plate 1 is an air cylinder 6, comprising a cylinder 7 secured between heads 8 and 9 fastened to the channel members by bolts 10. Rods 11 connect heads 8 and 9 to hold them in air tight relation with respect to cylinder 7. A piston rod 12 provided with head 13

40 of conventional construction operates in cylinder 7 and air is adapted to be admitted or exhausted, from above or below the head 13 in cylinder 6 by pipes 14 and 15 connected to a three-way valve 16 (operated by handle 17) and supply pipe 18, to raise or lower rod 12 in a well known manner. Secured to the upper end of rod 12 is a carriage 20 provided with rollers 21 which engage the flanges of channel members 2 and 3. A pin 22 is rigidly secured to carriage 20 and extends outwardly between the flanges of the channels. A transverse guideway 23 is formed in the carriage, below and parallel to pin 22, in which a second pin 24 is mounted for longitudinal

movement. A rearwardly extending bracket 55 25 is formed integral with carriage 20 and pivotally supports an arm 27 the free end of which is forked to engage a squared portion 28 formed on the rear end of pin 24. The forks of arm 27 are slotted at 30 to engage pins 31 formed integral with the side faces of part 28 thus forming a sliding connection between arm 27 and pin 24. Adjacent slots 30 60 arm 27 is provided on either side with projecting lugs 32. Secured to the rear flanges 65 of channels 2 and 3 are cam tracks 34 and 36 to which are pivoted at 38 and 40 arms 41 and 42. The latter are provided with inwardly projecting flanges 43 and 44 respectively which form part of the cam as later described. 70 The free ends of arms 41 and 42 are yieldingly held in position by bolts 46 and 47 passing through flanges 43 and 44 and tracks 34 and 36 as shown in Figures 1 and 3. Springs 48 and 49 normally maintain arms 41 and 42 75 against the lower heads of the bolts but permit the arms to swing upwardly as later described.

Secured between relatively fixed points on the channels 2 and 3 and the carriage 20 are two toggles, generally indicated at 50 in Figure 2. These toggles each comprise double arms 51 and 52 secured to a shaft 53 supported in bearings 54 secured to channels 2 and 3 at 55, and double arms 56 and 57 secured to 80 shafts 58 supported in bearings 59 formed integral with carriage 20 (see Figure 1). The two sets of arms are pivotally connected by pins 61 and the arms comprising each set are maintained in spaced relation by bearings 85 54 and 59 and by spacing sleeves 60 which surround pins 61. Pins 61 are extended at 62 to form supports for grooved rollers 63.

Slidably mounted between the forward flanges of channels 2 and 3 is a bracket 64 provided at its free end with a bag seat 65. The bracket 54 is vertically adjustable through rod 66 rotatably secured to the bracket and threaded through lug 67 formed in cross-piece 68 secured between the upper 100 ends of channels 2 and 4 by bolts 70.

The operation of the device is as follows: With the parts in the position shown in Figure 2 a bag 75 is positioned on member 65 with rolls 63 and pin 22 engaging the inner periphery of the bag and pin 24 engaging the outer periphery, as shown in dotted line in said figure. Air is now admitted to the lower

end of cylinder 7, thus raising carriage 20, carrying pins 22 and 24, and moving rolls 63 outwardly as shown in Figure 7. Upon continued upward movement, pin 24 folds the bag about rolls 63, the latter moving inwardly to the position shown in Figure 8. As the carriage 20 reaches the upper end of its travel lugs 32 engage pivoted arms 41 and 42 which yield against springs 48 and 49 to let the lugs 10 pass as shown in Figure 5. A raw tire casing 80 is now positioned over the folded bag as shown in Figure 9 and air pressure admitted to the upper end of cylinder 7 to move carriage 20 downwardly. As the carriage descends rolls 63 again move outwardly forcing the side portions of the bag into the casing. On the downward movement of the carriage lugs 32 engage flanges 43 and 44 of arms 41 and 42 thus withdrawing pin 24 as shown in Figure 20 6.

The bag being of resilient material tends to return to its normal shape when the restraint of pin 24 and rolls 63 are removed, and in returning to normal shape it tends to enter 25 the casing, this tendency aiding rolls 63 in forcing the bag into the sides of the casing as above described. Pin 22 acts to positively force the last portion of the bag into position. The casing with the bag enclosed is now removed.

As the carriage 20 approaches its lowest position lugs 32 strike the lower inturned portions of cams 34 and 36 thus returning pin 24 to its original position. It will be obvious 35 that the initial position and subsequent movement of rolls 63 may be varied by shortening or lengthening the members of toggles 50, as to accommodate a different size or character of bag.

Having described an illustrative embodiment of my invention, I claim:

1. A device of the character described comprising means engaging the inner periphery of a bag at spaced points, means to fold a portion of the bag inwardly between the engaging means and means to separate the latter as the bag is folded therebetween.

2. A device of the character described comprising means engaging the inner periphery of a bag at two spaced points, folding means engaging the outer periphery of the bag and adapted to fold a portion of the bag inwardly between the engaging means and means to separate the engaging means as the folding 50 means moves inwardly.

3. A device of the character described comprising means engaging the inner periphery of a bag at two spaced points, folding means engaging the outer periphery of the bag and adapted to fold a portion of the bag inwardly 60 between the engaging means, and means operatively connected to the folding means to separate the engaging means upon operation of the folding means.

4. A device of the character described com-

prising a support for a bag, a folding member engaging the outer periphery of the bag at a point substantially opposite the support, rolls engaging the inner periphery of the bag at points between the supporting and folding 70 means, means operatively connecting the engaging and folding means, means to reciprocate the folding means to simultaneously separate the engaging means and move the folding means and that portion of the bag in contact therewith between the engaging means.

5. A device of the character described comprising means to engage the inner periphery of a bag at spaced points, means to fold a portion of the bag inwardly between the engaging means, means to separate the latter as the bag is folded therebetween and thereafter return the latter to original position, means to again separate the engaging means to force the engaged portions into a tire casing positioned over the folded bag and means to force the folded portion of the bag into the tire casing.

6. A device of the character described comprising means engaging the inner periphery of a bag at two spaced points, folding means engaging the outer periphery of the bag and adapted to fold a portion of the bag inwardly between the engaging means and means to separate the engaging means as the folding 90 means moves inwardly, means to again separate the engaging means to force the engaged portions of the bag into a tire casing positioned over the folded bag and means to force the folded portion of the bag 100 into the tire casing.

7. A device of the character described comprising means engaging the inner periphery of a bag at two spaced points, folding means engaging the outer periphery of the bag and adapted to fold a portion of the bag inwardly between the engaging means, and means operatively connected to the folding means to separate the engaging means upon operation of the folding means, said connecting means operative to again separate the engaging means to force the engaged portions of the bag into a tire casing positioned over the folded bag and means to force the folded portion of the bag into the 115 tire casing.

8. A device of the character described comprising a support for a bag, a folding member engaging the outer periphery of the bag at a point substantially opposite the support, rolls engaging the inner periphery of the bag at points between the supporting and folding means, means operatively connecting the engaging and folding means, means to reciprocate the folding 120 means to simultaneously separate the engaging means and move the folding means and that portion of the bag in contact therewith between the engaging means, said connecting means operative to again separate 125 the engaging means.

130

the engaging means upon return reciproca-
tion of the folding means to force the en-
gaged portions of the bag into a tire casing
positioned over the folded bag and means
5 to force the folded portion of the bag into
the tire casing.

9. A device of the character described
comprising a support for a bag, a folding
member engaging the outer periphery of
10 the bag at a point substantially opposite the
support, rolls engaging the inner periphery
of the bag to simultaneously separate the
engaging means and move the folding means
and that portion of the bag in contact there-
15 with between the engaging means, said con-
necting means operative to again separate
the engaging means upon return reciproca-
tion of the folding means to force the en-
gaged portions of the bag into a tire casing
20 positioned over the folded bag and means
to force the folded portion of the bag into
the tire casing.

10. Apparatus of the class described com-
prising two pairs of presser elements, the
25 elements of each pair being movable rela-
tively toward and from each other and
adapted to receive a pressure bag and col-
lapse the same.

11. Apparatus of the class described com-
prising a pair of presser elements relatively 30
movable toward and from each other and
adapted to receive a pressure bag, and a sec-
ond pair of presser elements movable toward
and from each other substantially at right
35 angles to the first pair.

12. An air bag folding and inserting de-
vice comprising means for folding a portion
of an air bag, means to reciprocate the fold-
ing means, means to engage the inner per-
iphery of the bag at points spaced from
40 each side of the folded portion, means opera-
tively connecting the reciprocating, engag-
ing and folding means to draw the outer ends
of such folded portion of the bag together as
45 the folding means is reciprocated to form
the remainder of the bag into a substan-
tially annular shape, and means to force the
bags into a tire casing.

13. Apparatus of the class described, com-
prising means for first flattening a portion 50
of an air bag, and means for subsequently
folding the bag inwardly at the flattened
portion.

In testimony whereof I have signed my
name to the above specification.

GEORGE F. WIKLE.
